UNITED STATES PATENT OFFICE

2,438,943

SANDBLASTING MACHINE

Albert J. Porcelli, New York, N. Y.

Application December 23, 1946, Serial No. 718,097

5 Claims. (Cl. 51—8)

(Granted under the act of March 3, 1883, as amended April 30, 1928; 370 O. G. 757)

1

This invention relates to improvements in sandblasting machines in which sand or a similar powdered or granular abrasive is impelled against an object to be scoured or polished by application of the force of compressed air.

The primary object of this improvement is to provide a novel mechanical means for scouring or polishing an object.

A further object is to provide a sandblasting machine of simple and durable construction wherein the abrasive action will be substantially uniform over the entire surface being scoured or polished.

Another object is to provide a sandblasting machine having a filter adapted to absorb matter abraded from the surface being scoured or polished.

A further object is to provide a sandblasting machine in which the sand or other abrasive employed is reclaimed and reused.

Another object is to provide a sandblasting machine that will reduce substantially the occupational hazard of exposure to atmosphere containing concentrations of the finely divided particles that are products of the operation.

Further objects and advantages of this invention, as well as its construction, arrangement and operation, will be apparent from the following description and claims in connection with the accompanying drawing, in which

Fig. 1 is a plan view of a sandblasting machine partly broken away, showing a preferred embodiment of this invention; and

Fig. 2 is a sectional elevation thereof taken on the line 2—2 of Fig. 1 and showing an object suspended in the tank of the machine.

Similar numerals refer to similar parts throughout the several views.

A cylindrical tank or cannister 11 mounted on legs 13 is provided with means to suspend an object to be scoured or polished, such as a plurality of angle irons 15 secured to the inner wall of said tank. A conduit 17 provided with a pressure valve 19 is supported by braces 21 on the outer wall of said tank and is led into said tank through a port 23 adjacent the floor 25 thereof. Convolutions of the conduit, preferably in the pattern of a decreasing spiral, cover a substantial portion of the floor of said tank, and a plurality of perforations 27 in the convoluted portion of said conduit are adapted to direct a stream of air vertically upward.

The sandblasting machine is provided with a cover 29 having an annular resilient gasket 31, which seals said cover hermetically to the upper periphery of the tank 11, said engagement being retained by a plurality of clamps or locks 33. An annular inner flange 35 on the lower periphery of the rim of the cover facilitates seating said cover on the tank and the resilient ring 37 mounted on

2

the crest of said flange aids in limiting displacement of the object being scoured.

A portion of the cover 29 is provided with a filter that permits egress of air from the tank 11 while removing foreign substances from such air. The preferred embodiment of such filter comprises successive laminations of screen 39, matted fibers 41, porous carbon 43, matted fibers 45 and screen 47 packed in horizontal layers within the rim of said cover to form the body thereof.

The cover 29 is further provided with a suitable handle 49 to facilitate placement and removal.

When a quantity of sand or similar powdered or granular abrasive 51 is placed on the floor of the tank, compressed air admitted to the chamber of the tank by opening the valve 19 discharges through the perforations 27 in the convoluted portion of the conduit and impels particles of said sand against the object 53, thereby effecting scouring or polishing action upon such object. The sand is repelled by impact against such object or against the laminated filter and falls toward the floor of the tank, while the air is released through said filter.

It is apparent that solid matter abraded from said object is either commingled with the sand, thereby becoming a supplementary abrasive, or adheres to the filter, and that gaseous matter 30 is neutralized by the chemical action of the filter. It is further apparent that the repelled sand and solid abraded matter is again accelerated upward against the object and that the cycle is repeated 35 continually as long as pressure of air is maintained. The plurality of perforations in the convoluted portion of the conduit provides an upward force that is substantially uniform over the entire circumference of the tank. When the valve 40 is closed, the sand and abraded solid matter rest on the floor of the tank and the operation can be repeated upon another object without replenishing the abrasive, since there is substantial reclamation of the sand used.

Various modifications and changes can be made in the above device without departing from the scope of the invention.

The invention described herein may be manufactured and used by or for the Government of 50 the United States of America for governmental purposes without the payment of any royalties thereon or therefor.

I claim:

1. A sandblasting machine comprising a tank adapted to contain a quantity of sand, a conduit 55 adapted to conduct compressed air to the interior of said tank, the portion of the conduit within said tank being convoluted over the floor of said tank and having a plurality of perforations adapted to facilitate upward flow of air, means

for controlling the flow of compressed air and means for suspending an object in said tank.

2. A sandblasting machine comprising a tank adapted to contain a quantity of sand, a conduit adapted to conduct compressed air to the interior of said tank, the portion of the conduit within said tank being spirally convoluted over the floor of said tank and having a plurality of perforations adapted to facilitate upward flow of air, means for controlling the flow of compressed air, means for suspending an object in said tank and a cover for said tank having a plurality of perforations.

3. A sandblasting machine comprising a tank adapted to contain a quantity of sand, a conduit adapted to conduct compressed air to the interior of said tank, the portion of the conduit within said tank being convoluted over the floor of said tank and having a plurality of perforations adapted to facilitate upward flow of air, means for controlling the flow of compressed air through the conduit, means for suspending an object in said tank and a cover for said tank having an air filter integral therewith.

4. A sandblasting machine comprising a tank adapted to contain a quantity of sand, a conduit adapted to conduct compressed air to the interior of said tank, the portion of the conduit within said tank being convoluted over the floor of said tank and having a plurality of perforations adapted to facilitate upward flow of air, means for controlling the flow of compressed air through the conduit, means for suspending an object in said tank, a cover for said tank having a filter

integral therewith, said filter being composed of horizontally disposed laminations of a plurality of porous substances, and means for hermetically sealing said cover to said tank.

5. A sandblasting machine comprising a tank adapted to contain a quantity of sand, a conduit adapted to conduct compressed air to the interior of said tank, the portion of the conduit within said tank being spirally convoluted over the floor of said tank and having a plurality of perforations adapted to facilitate upward flow of air, means for suspending an object in said tank, a cover for said tank having a filter integral therewith, said filter being composed of horizontally disposed laminations of a plurality of porous substances, an annular inner flange on the lower periphery of the rim of said cover, a resilient ring mounted on the crest of said flange and means for hermetically sealing said cover to said tank.
